UNITED STATES PATENT OFFICE

103,424

DESIGN FOR A TEXTILE FABRIC

Curt Erwin Forstmann, Montclair, N. J.

Application May 18, 1935, Serial No. 56,906

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing forming part thereof.

In the drawing, the sole figure of which is a plan view of a piece of the textile fabric embodying the design of the present invention, the cloth depicted is of a single color.

The design is a pattern of diagonal stripes of fugitive nature composed of long weftwise bars with short pairs intervening, the bars being so staggered, and arranged with such degree of contiguity as to give a reticulated appearance to the surface of the fabric.

Two of the repeated diagonal stripes are indicated between broken lines in the drawing.

I claim:

The ornamental design for a textile fabric as described and shown.

CURT ERWIN FORSTMANN.
